UNITED STATES PATENT OFFICE

2,067,249

MINE CAR

Walter H. Statler, Johnstown, Pa., assignor to
Bethlehem Steel Company, a corporation of
Pennsylvania

Application January 6, 1932, Serial No. 585,015

6 Claims. (Cl. 105—364)

My invention relates to the construction of mine cars and more especially to that type of mine car which is equipped with a swinging end gate that is automatically latched when closed and which is adapted to be automatically tripped to open for the purpose of releasing the car loading as it arrives at the unloading bins or chutes.

An object of my invention is to provide means in combination with an end-gate latching mechanism which first automatically engages the latch operating means provided at the unloading bins or chutes for the purpose of unlatching the end-gate, and thereafter automatically disengages the latch operating means as the car assumes its unloading position.

A further object of the invention relates to the manner of constructing a portion of the axle mountings by means of a downwardly projecting steel plate riveted to the side sills and reinforced on the inside by a pressed steel plate bracket. This construction being arranged in pairs at each axle housing and the pairs being united by a flat bar attached to the bottoms of the brackets.

Another object of my invention relates to the floor sill and bumper construction in having the floor and side sills extend beyond each end of the car and in utilizing these sill extensions to attach bumper members thereto with the result that a very rugged design is obtained in which the shocks received by the bumpers are most efficiently distributed throughout the full length of the car.

Other objects of my invention relate to certain novel features of construction, combination, and arrangement of parts which will be hereinafter more fully described and particularly pointed out in the appended claims, reference being had to the accompanying five sheets of drawings in which:

Fig. 1 is a top plan view of a mine car embodying my improvements;

Fig. 2 is a side elevation of the same car;

Fig. 3 is a rear end elevation with axles and axle mountings removed.

Fig. 4 is a front elevation;

Fig. 5 is a part transverse section taken along the line 5—5 of Fig. 1;

Fig. 6 is a part vertical section through a bumper taken along the line 6—6 of Fig. 1;

Fig. 7 is a part horizontal section taken along the line 7—7 of Fig. 4;

Fig. 8 is a part vertical section taken along the line 8—8 of Fig. 4;

Fig. 9 is a plan view enlarged showing the detail structure of the spring draw-bar mechanism;

Fig. 10 is a transverse sectional elevation taken along the line 10—10 of Fig. 9; and

Fig. 11 is a longitudinal sectional elevation taken along the line 11—11 of Fig. 1.

In the drawings the numeral 10 indicates the mine car in which is embodied my improvements, and in Fig. 2 the mine car 10 is shown in position at the automatic unloading point of the tipple. The automatic unloading means is not a part of my invention and any arrangement would be suitable which would comprise a car tilting device such as the tilting platform 11, and a latch operating mechanism such as the biased lever device 12, shown diagrammatically in Fig. 2.

The floor of the car 10 comprises a steel top-plate 13, a steel bottom-plate 14, and an intermediate wood plank filling 15, riveted together as 16. The sides 17 of the car 10 are formed each of a single steel plate having its upper edge portion bent or rolled over to form a tubular top edge 18 with the edges 19 bent flat against the outside of the side sheet and riveted thereto. The lower edges of the sides 17 are riveted to upturned side flanges 20 of the bottom plate 14.

The rear car-end 21 is formed of a single steel plate and has its upper edge portion bent in the same manner as just described for the sides 17, while the bottom edge is secured to the floor by means of an angle bar 22, the vertical leg of which is riveted to the bottom edge of the rear car-end 21 while the horizontal leg is inserted between the bottom plate 14 and the plank filling 15 and is included in the riveting thereof. The rear vertical edges of the sides 17 and the adjacent vertical edges of the rear car-end 21 are joined together and reinforced by an angle bar 22 riveted thereto.

Attached to the inside of the front upper corners of the sides 17 are the shaft support brackets 23. The brackets 23 extend above the top edge of the sides 17 and are adapted to receive the shouldered and threaded ends 24 of the shaft 25. The shaft 25 is secured in the brackets 23 by the cotter nuts 26, and by reason of the shouldered engagement, the shaft 25 acts to maintain the upper front corners of the sides 17 in rigid spaced relation.

The front end of the car 10 is closed by a swinging end or door 27. The door 27 comprises a steel plate 28 having its upper edge bent to the outside in the same manner as hereinbefore described for the upper edges of the sides 17, while

its lower edge is similarly bent but in an opposed direction. Riveted on the inside face of the plate 28 at the top are the hinges 29 which in turn are pivotally mounted upon the shaft 25. Collars 30 integral with the shaft 25 engage opposed faces of the outer pair of hinges 29, thus positioning the door 27 in relation to the sides 17. For stiffening purposes angle bars 31 at the ends, and a pressed steel recessed plate or stake 32 at the vertical center, are riveted to the inside face of the plate 28. For latching the door 27, the keeper plates 33 are riveted to the outside of the sides 17 at the lower front corners. On the front face of the plate 28 at the lower corners are riveted the latch guides 34 which guide the outer ends of the substantially horizontal latches 35 while their inner ends are pivotally attached to a vertical latch slide bar 36 by suitable means 37. The latch slide bar 36 is slidably mounted in the guides 38 and 39 riveted to the outside face of the plate 28 on the vertical center. The upper end 40 of the latch slide bar 36 is bent outward for a purpose to be hereinafter described. Also riveted on the outside face of the plate 28 on either side of the vertical center and just above the guide 38 are the cam brackets 41 having the upward and outward sloping edges 42, the purpose of which will hereinafter be described.

To give added rigidity and strength, a pressed steel recessed plate or stake 43 similar to the stake 32 on the door plate 27 is riveted to the inside face of the rear end plate 21. A similar stake 44 is riveted to each side plate 17 on the outside at the center, while other similar but longer stakes 45 are positioned midway of each half of and one at the front of each of the side plates 17. The stakes 45 extend downward below the floor-line and are there riveted to cantilever brackets to be described hereinafter.

Outer floor sills 46 and inner floor sills 47 run lengthwise of the car and extend beyond the floor limits at each end. Standard ship channels are utilized for the outer sills 46 while commercial structural channels are utilized for the inner sills 47. The floor sills 46 and 47 are positioned with their webs vertical and having their upper flanges riveted to the bottom-plate 14. Other rivets 48 placed at intervals along the sills 46 embrace in addition the plank-filling 15 and the top-plate 13. It will be noted that the sills 46 and 47 divide the area beneath the floor longitudinally into five substantially equal spaces which proportionally distributes the strength and support of the sills to the floor.

It will also be noted that each of these spaces is utilized for one of the various structural elements of the tractive gear. The center space houses at each end a spring draw-bar mechanism 49. The outer spaces over-lie the wheels 50 and the brake mechanism 51, while the intermediate spaces extended include the bumpers 52.

The spring draw-bar mechanism 49 shown in enlarged detail in Figs. 9, 10 and 11 comprises a draw bar 52' adapted at its outer end 53 for a conventional car coupling and at its inner end 54 for a key 55 retained in place by cotters 56. The shank 57 of the draw bar 52' is square in cross-section and has slidably mounted thereon in pairs the yoke-plates 58. For the purpose of ready assembly the bearing aperture 59 of the yoke-plates 58 for the shank 57 is open to one side, and as assembled in pairs the open side of one plate 58 is opposed to the closed side of the other plate 58. Intermediate of the pairs of yoke-plates 58 and to each side of the shank 57 are

compression springs 60 retained in place therebetween by the bolts 61 slidably mounted in the yoke-plates 58 and retained therein by the cotters 62 and heads 63. The draw-bar mechanism 49 comprising the parts 52' to 63 inclusive just described constitutes a unit slidably assembled between the sills 47 on the sides and between the bottom-plate 14 above and the plate 64 below removably attached to the sills 47 by means of the bolts 65. For the purpose of locating the relative longitudinal position of the draw-bar mechanism 49 and to transmit the draw bar pull to the car 10 the outer pair of yoke-plates 58 engage the pull-blocks 66 riveted to the sills 47. Reinforcing the sills 47 at this point are the angle bar braces 67, the angle bar braces 68, and the transverse channel bar 69. For the purpose of giving initial tension to the compression springs 60 and to maintain the draw-bar mechanism in its normal relative longitudinal position the inner pair of yoke-plates engage normally the stop-blocks 70 riveted to the sills 47 in such spaced relation relative to the pull-blocks 66 that the desired initial compression of the spring 60 is obtained. Reinforcing the sills 47 at this point are the plate 71, the angle bar braces 72, and the transverse channel bar 73. Additional bracing of the sills 46 and 47 at each end of the car 10 comprises the transverse channel bar 74, and the angle bar brace 75. The cantilever brackets 76 are additional bracing supplied to the open front end, being riveted on their inner ends to the sills 46 and on their outer ends are riveted to the lower end of the end stake 45 as shown in Fig. 2. It should be noted here that no floor riveting has been shown in Figs. 9, 10 and 11. Also, for convenience sake, a detail showing the rear car end 21 connection to the floor construction by means of the angle 22' has been included in Fig. 11.

The wheels 50 are rotatably mounted in pairs 40 on the axles 77. The axles 77 have fixedly mounted thereon the inside pedestal bearings 78 which are vertically slidably mounted in the pedestals 79.

The pedestals 79 are attached to the outer floor sills 46 in pairs, two pairs to a sill. Each pedestal 79 comprises a pressed steel plate bracket 80 with a bearing wear-plate 81 riveted thereto. The brackets 80 are riveted to the under side of the sills 46, each with its wear-plate 81 opposed to and engaged with a suitably flanged side of a pedestal bearing 78, and thus act to fix laterally the wheels and axles in the car 10. The riveting at each of the brackets 80 to the floor sills 46 embraces a spring locating strip 82 and the outer ends of the transverse sill reinforcing strips 83 and 84. The strips 83 and 84 extend transverse the under sides of the floor sills 46 and 47 and in addition to the riveting of the sills 46 are also riveted to the sills 47. The spring locating strips 82 have depressions 85 formed therein which act as centering means for the compression springs 86. The compression springs 86 are mounted in suitable recesses 87 in the pedestal bearings 78 and react against the spring locating strips 82. The springs 86 are designed so that the reaction of all the springs combined acting against the floor sills 46 is sufficient to carry the weight of a loaded car without fully compressing the springs 86, thus leaving a margin for absorbing shocks. To maintain the pedestal bearings 78 in their normal position under the combined spring load and to further strengthen the pedestal construction, the pedestal tie bars 88 connect each pair of the brackets 80 by being attached to the under side 75

thereof by the bolts 89. The outer vertical faces of the brackets 80 are riveted to the brace plates 90 and 91 riveted to the vertical web of the outer sills 46. For further reinforcing the pedestal construction the cantilever brackets 92, similar to the cantilever brackets 76, are included in the riveting of the brace plates 90, the bottom-plate 14, and the bottom of the intermediate stakes 45.

Extending transversely of the underside of the car body at the center are additional reinforcing members 93, 94, 95 and 96 that are similar in structure and function to the channel bar 69, the angle bars 67, the channel bar 74, and the angle bar 75, respectively, hereinbefore described.

The brake mechanism 51 is arranged to be operated from either side of the rear end of the car 10 by means of the levers 97 and 98. The operating levers 97 and 98 are pivotally mounted upon the brackets 99 by suitable means such as the bolts 100. The brackets 99 are riveted to the outside of the plate 21 and as shown are flanged U-shaped castings or forgings. The upper ends of the levers 97 and 98 are guided and their pivotal movement limited by the guide ratchets 101 which are riveted to the outside of the plate 21 and are provided with suitable toothed notches 102 which, in a well known manner, are adapted to engage toothed edges 103 on the levers 97 and 98 to retain the latter in their braked position. The levers 97 and 98 in their normal unbraked position are inclined toward the vertical center of the plate 21 and are operated for braking, as already stated, from either side of the rear of car 10. It is equally desirable that both the levers 97 and 98 may be disengaged from either side of the car 10, and this I provide for by pivotally mounting the releasing crank 104 in the bearings 105 and 106 attached to the rear end plate 21. The releasing crank 104 has the cranked portions 107 and the handles 108, both of which in their normal position hang downward due to gravity. In this normal position the cranked portions 107 engage the inside of the levers 97 and 98 when the latter are in their engaged or braked position. To disengage the levers 97 and 98 it is readily seen that it is only necessary to operate the releasing crank 104 from either side by means of the handles 108 to force the cranked portions 107 against the levers 97 and 98 until the latter are disengaged from the guide ratchet notches 102. In order that the brake mechanism 51 may be operated from either side of the car 10 it is necessary that the two levers 97 and 98 be linked together to move in unison in opposite directions. This I accomplish by means of the forked end link 109 which is pivotally attached to an extension 110 on the lever 97 below its pivotal point 100 and to the lever 98 above its pivotal point 100. Each of the levers 97 and 98 are pivotally connected above their pivotal points 100 to the inner end of link 111. The outer ends of the links 111 are pivotally attached to the upwardly extending crank arms 112 of the brake shafts 113. The brake shafts 113 extend along the rear half of the underside of the car 10 in the corners formed by the outside vertical face of the sills 46 and the bottom plate 14. To permit of rotational movement the shafts 113 are loosely mounted in bearing brackets 114 and 115 riveted to the rear end of the sills 46 and bottom plate 14 and in bearing brackets 116 riveted to the plates 91. The shafts 113 are fixed longitudinally in their bearings by means of shoulders 117 engaging op-

posed faces in the bearing brackets 115 and 116. The forward ends of the shafts 113 terminate in crank arms 118 having pivotal attachment to the upper end of the yoked links 119. The lower ends of the yoked links 119 act as the pivotal connections for the upper ends of the toggle links 120. The lower ends of the toggle links 120 are pivotally attached to the brake shoes 121 which in turn are pivotally supported at their upper ends by the lower ends of the hanger links 122. The hanger links 122 at their upper ends are pivotally supported by the angle brackets 123 attached to the car bottom by suitable means 124. The operation of the brake shoes 121 by means of the shaft 113 and connecting parts is self evident and need not be herein further described.

The bumpers 52 are formed by extending the floor sills 46 and 47 beyond the ends of the floor plates and joining the extended ends of the floor sills together in pairs on each side of the longitudinal center line of the car 10. As shown in Fig. 6 together with Fig. 1, the ends of the floor sills 46 and 47 are joined together across the top by the plates 125 and across the bottom by the plates 126, these plates extending outward beyond the ends of the floor sills 46 and 47. The outer end edges of the plates 125 and 126 are curved to correspond to the web contour of filler channel bars 127 having inwardly directed flanges 128 which are riveted to the plates 125 and 126. A reinforcing bar 129 is curved to fit the interior of the web of the channel bar 127, and fitted inside of this is a wood filler block 130 which is embraced by the riveting of the channel bar 127 to the plates 125 and 126. Floor sill reinforcing bars 131 extends transverse of the floor sills 46 and 47 on the under side thereof at each end and are riveted thereto just inside the buffer bottom plates 126.

Having thus described the structure of my mine car I will now describe its operation upon its assumed arrival at the tipple loaded and ready to be unloaded. The car 10 as loaded is run onto a car tilting device 11 at the unloading point which may, in the tilting platform type shown diagrammatically in Fig. 2, include stops 132 for the wheels 50. As the car wheels 50 engage the stops 132 the arrested momentum of the loaded car tends to tilt the car 10 and the platform 133 forward about the pivot point 134 until they come to rest at a suitable unloading angle by engaging a stop not shown. At the instant the car wheels 50 engage the stops 132 the upper end 40 of the latch slide bar 36 comes into engagement on its under side with the end 135 of the biased lever device 12 (shown diagrammatically) pivotally mounted to the structure 136 of the tipple. The action of the biased lever device 12 in engagement with the latch slide bar 36 is such that as the car 10 tilts forward about the platform tilting point 134 the latch slide bar 36 is raised, relatively to its initial position on the front door 27, which action results in withdrawal of the latches 35 from engagement with the keeper plates 33. As the latches 35 disengage, the weight of the coal against the swinging door 27 causes the latter to swing outward and thus give ready exit to the unloading coal. As the car 10 continues to tilt downward in its unloading operation after the latches 35 are disengaged and the door 27 has swung open, it is desirable that the biased lever device 12 having done its work be disengaged. This is brought about by the outward sloping edges 42 of the cam bracket 41 engaging 75

the end 135 of the biased lever and gradually disengaging the latter from the latch slide bar end 40. When the point of disengagement is reached as shown in dotted lines in Fig. 2 the 5 latch slide bar 36 drops due to the action of gravity to its initial position shown in Fig. 4. This also returns the latches 35 to their initial position. When the car is unloaded and is returned to a horizontal position, the door 27 10 tends, due to the action of gravity, to return to its closed position, and this return movement brings the outer ends of the latches 35 into engagement with the sloping edges 137 of the keeper plates 33. Since the latches 35 are pivotally attached to the latch slide bar 36 at 37 they are free to rise along the slopes 137 in the guides 34 until the door becomes closed when the latches 35 then drop into latched engagement with the keeper plates 33 as shown in Fig. 20

2. The car 10 is then again ready to be loaded.

Although I have described and illustrated my invention in considerable detail, I do not wish to be limited to the exact and specific details thereof, as shown and described, but may use such modifications in, substitutions for or equivalents thereof, as are embraced within the scope of my invention or as pointed out in the claims.

Having thus described my invention what I claim as new and desire to secure by Letters Patent is:

1. In a mine car structure, laterally spaced longitudinal channel sills arranged in pairs, the ends of the sills extending beyond the ends of the car body, car bumpers each comprising an upper and a lower horizontally disposed plate riveted to the extended ends of each pair of sills and extending outwardly therefrom, a bumper channel having its flanges riveted to the extensions of said plates and its web forming an edge 35 closure between said plates, a wood filler block 40 enclosed by the sills and said plates and embraced by the riveting of said plates to said bumper channel, and a reinforcing plate vertically abutting the inner face of the web of said bumper channel and the outer face of said wood filler block.

2. In a mine car, laterally spaced longitudinal sills, and axle pedestal bearings comprising, one piece pedestal brackets arranged in spaced relation in pairs, each bracket composed of a vertical longitudinally disposed web, a vertical flange, and horizontal upper and lower flanges, the said flanges extending laterally toward the longitudinal center of the car, the upper flanges of each 50 pair attached to a sill, and the vertical flange of each pair disposed in opposition to one another, wear plates attached to the opposed faces of the vertical flanges, a bar attached to the lower flanges of each pair, and a vertical longitudinally disposed plate attached to each bracket and to

the adjacent sill, the said plate extending beyond the bracket along the sill on that end opposed to the vertical flange.

3. In a mine car, laterally spaced longitudinal sills, and axle pedestal bearings comprising, one 5 piece pedestal brackets arranged in spaced relation in pairs, each bracket composed of a vertical longitudinally disposed web, a vertical flange, and horizontal upper and lower flanges, the said flanges extending laterally toward the longitudinal center of the car, the upper flanges of each pair attached to a sill, and the vertical flange of each pair disposed in opposition to one another, a bar attached to the lower flanges of each pair, and a vertical longitudinally disposed plate attached 10 to each bracket and to the adjacent sill, the said plate extending beyond the bracket along the sill on that end opposed to the vertical flange.

4. In a mine car, laterally spaced longitudinal sills, and axle pedestal bearings comprising, one 20 piece pedestal brackets arranged in spaced relation in pairs, each bracket composed of a vertical longitudinally disposed web, a vertical flange, and horizontal upper and lower flanges, the said flanges extending laterally toward the longitudinal center of the car, the upper flanges of each pair attached to a sill, and the vertical flange of each pair disposed in opposition to one another, wear plates attached to the opposed faces 25 of the vertical flanges, a bar attached to the lower flanges of each pair, and a vertical longitudinally disposed plate attached to each bracket and to the adjacent sill.

5. In a mine car, laterally spaced longitudinal sills, and axle pedestal bearings each comprising, 35 reinforcing plates attached to the outer face of a sill in vertical longitudinal spaced relation, two one-piece pedestal brackets each bracket having a vertical longitudinally disposed web attached to the inner face of a reinforcing plate, and laterally extending flanges, of which the upper flange is attached to a sill, a vertical flange of each bracket in opposition with a vertical flange of the other bracket, wear plates attached to the inner opposed faces of the vertical flanges, a pedestal bar attached at its ends to the lower flanges of each bracket.

6. In a mine car, laterally spaced longitudinal sills, and axle pedestal bearings each comprising, reinforcing plates attached to the outer face of a 50 sill in vertical longitudinal spaced relation, two one-piece pedestal brackets each bracket having a vertical longitudinally disposed web attached to the inner face of a reinforcing plate, and laterally extending flanges, of which the upper flange 55 is attached to a sill, a vertical flange of each bracket is in opposition with a vertical flange of the other bracket, a pedestal bar attached at its ends to the lower flanges of each bracket.

WALTER H. STATLER. 60
